UNITED STATES PATENT OFFICE.

JOHN J. DITTCEN, OF CINCINNATI, OHIO.

PROTECTING-CELL FOR CIGARS.

1,209,816.

Specification of Letters Patent. Patented Dec. 26, 1916.

Application filed June 24, 1915. Serial No. 36,131.

To all whom it may concern:

Be it known that I, JOHN J. DITTCEN, a citizen of the United States of America, and a resident of Cincinnati, in the county of 5 Hamilton and State of Ohio, have invented a certain new and useful Improvement in Protecting-Cells for Cigars, of which the following is a specification.

This invention relates to cigar pouches 10 or pockets that are connected in series and adapted to be compactly wound, when filled, in spiral form and in predetermined numbers to suit the size of can or other receptacle in which the goods are to be closely 15 packed on end, for both display and sale as well as to enable the salesman or the consumer to readily extract one or more of the cigars without abrading-contact with the remaining cigars in the package and, also, 20 without allowing the said remaining cigars in the package to fall or move therein from their originally-placed upright or on-end position.

The object of the present invention is to 25 provide a series of independent, open, tubular pouches or pockets with a continuous imperforate or unbroken, intact backing-strip that is adapted to protect and support them in parallel array along one face thereof, such 30 backing-strip being of a pliable or flexible material that is readily adapted to bend or hinge along transverse lines between each pair of open, tubular pouches or pockets so that the spiral-winding of a number of open, 35 tubular pouches or pockets mounted along one face of said pliable strip can be readily accomplished and in just as tight or compact condition as it is advisable to pack the cigars in associated-relation subject to the proper 40 removal or extraction of individual cigars from the respective pockets without injury to any of them.

The details of structure, that will include 45 those of the individual, open, tubular pouches or pockets themselves, will be fully hereinafter described and then the entire device more particularly pointed out in the claims that follow.

In the accompanying sheet of drawings, 50 Figure 1 is a plan view of the form of blank used in the make-up of the preferred structure of individual pouch or pocket connected with my invention herein; Fig. 2, an elevation showing a series of three open, tubular 55 pouches or pockets attached to the face of a continuous, imperforate or intact backing-

strip, the latter being shown broken off at opposite sides of the series of said three pouches; Fig. 3, a plan view of a can or other receptacle used to contain the cigars 60 when placed in a series of open, tubular pouches or pockets that are attached to my improved pliable winding and continuous, intact backing strip, the lid of such receptacle being removed and showing the cigars 65 as they would appear on display for sale and individual or separate extraction from the respective pockets for use; and Fig. 4, a fragmentary perspective view showing a strip of continuous, imperforate, intact back- 70 ing-material having a series of three open, tubular pouches on its face, with such backing-strip and the pouches so folded as to be ready for further folding into flat closed relation similar to accordion-plaits 75 for compactness when out of use but ready for spreading open, as seen in said Fig. 4, for the convenient insertion of the cigars.

1 indicates an elongated strip of equal width throughout and made of paper or 80 other suitable pliable material that is continuous, unbroken and intact its entire length; 2, each one of a series of open, tubular pouches or pockets arranged and used in parallel array along one face of said strip 85 1, the latter forming a backing therefor; and 3, an extended or protruding mouth or lip at the opposite ends of each pouch, preferably of arc-shape and finely serrated, as shown at 4, for toning or softening the 90 otherwise sharp edge.

The pouches 2 are each provided with downwardly-curved or concave edges 5 at their opposite ends, on reverse sides of the pouch, adapting the latter to be an open or 95 bottomless, tubular one, and facilitating the insertion of the cigars when the protruding portions 3 are depressed by the entering-end of the cigar prior to its further or full insertion.

Each pouch is made of a strip of paper or the like cut into the blank-form seen in Fig. 1. The blank-form is made with its upper edge downwardly-curved at its middle-portion 5 and with upwardly-curved opposite ends α , α , that when brought together form the upper protruding-lip 3 when the blank is folded along the dotted-lines b , b and with their opposite longitudinal-edges c , c duly lapped and stuck together. The lower edge 110 of the said blank-form has a central protruding-portion 3 that develops or extends

laterally into the opposite inwardly-curved edges *d*, *d* subsequently forming the inwardly-curved part 5 when said edges *c*, *c* are lapped and stuck together. This blank-form when folded along the dotted-line *b*, *b* and with the edges *c*, *c* stuck together, constitutes my preferred form of pouch and the opposite edges of said blank-form are finely serrated, as shown at 4, for the purpose previously described. The pouch is a tubular or bottomless one, as above stated, and is adapted to the ready insertion of cigars at either end thereof, or likewise extraction therefrom, so that when a series of the open, tubular pouches is transversely attached in juxtaposition and in parallel array along one face of the continuous, unbroken and intact backing-strip 1 it is quite plain that whichever edge of the elongated strip, carrying the pouches, is before the person filling the pouches with cigars, such cigars can be readily inserted into place and, when the desired number of cigars has been placed in rotation in the pouches along the backing-strip, the latter is cut off at the last-filled pouch ready for compactly-rolling into the spiral-form seen in Fig. 3, the backing 1 being toward the person, with the filled pouches facing outwardly when the rolling of the package begins and thereby enabling a much better result, as the filled pouches will pack closer and the fresh or moist cigars given the desired flattened surfaces, the material of the backing readily hinging or bending between adjacent pouches and the latter assuming the relation to each other that is well shown in Fig. 3.

6 indicates a metal can, or a suitable vessel of any other material adapted to hold the customary quantity of cigars 7 in an upright or "on-end" position that is adapted to be exposed to view for inspection or display and, also, for the ready withdrawal of one or more of the cigars from their respective pockets without disturbing the remainder, such remainder remaining in their upright "on-end" normal position without liability to drop to one side or the other, or to fall in the receptacle, and the continuous strip 50 with its attached pockets thus holding all the cigars in an upright position until the last one has been removed from place in the package, and preventing injury or damage to the goods. The pouches may be made of moisture-proof material, and the backing 1 is intended to remain in the receptacle and to both protect and support the filled pouches while in said receptacle. The complete package can be readily reversed in the receptacle at any desired time, or even when it is partially filled for the inspection of both ends of the goods.

Fig. 4 has been placed on the drawings to

show how the open, tubular pouches and the backing can be folded or bent to enable them to be brought together in closed relation and flattened form, similar to accordion-plaits, in which flattened form they are packed in stock and readily adapted to be thrown into the open-position shown in Fig. 4 for the insertion of the cigars, only a few of the pouches being shown on the backing 1, but sufficient to make the point clear as to how the backing and open pouches are adapted to be folded for the accordion-plait relation. It is quite plain, too, that the continuous, imperforate backing-strip 1 facilitates the desired close winding or rolling-up of the required number of cigars by the packer and his then placing them in the vessel or package for sale and use.

I claim:—

1. A series of open, tubular pouches for use in supporting and protecting cigars packed in sales-receptacles and to permit the ready withdrawal of each cigar from its particular pouch, such series comprising an imperforate, flexible backing-strip and a longitudinally contiguous but disconnected series of parallel, elongated tubes whose backs are each attached along one face of said backing-strip and the latter adapted to be flexed in either direction between said disconnected tubes whereby the disconnected series of tubes may be tightly wound into a spiral bunch with the cigars held longitudinally upright within the said sales-receptacles to facilitate their inspection and, also, their removal therefrom, the latter either singly or as an entire unwound bunch, as desired.

2. A series of open, tubular pouches for supporting and protecting cigars packed in sales-receptacles, comprising a flexible, imperforate, continuous paper backing-strip and a longitudinally contiguous but disconnected series of elongated, paper tubes whose backs are stuck transversely along one face of said flexible backing-strip, whereby the pliability of said backing-strip between the contiguous but disconnected tubes facilitates and permits the rolling of the series of mounted tubes for ready and compact insertion in said sales-receptacles with their cigar-contents longitudinally disposed in an upright, endwise-display position therein and for ready individual removal of said cigar-contents from the respective tubes free from abrading-contact with each other and from leaning or falling sidewise at any time in the said sales-receptacles.

JOHN J. DITTCGEN.
